UNITED STATES PATENT OFFICE.

WILLIS SMITH FARNSWORTH, OF SAN FRANCISCO, CALIFORNIA, ASSIGNOR TO COIN CONTROLLED LOCK COMPANY, OF SAN FRANCISCO, CALIFORNIA, A CORPORATION OF CALIFORNIA.

LOCK-GUARD.

1,160,978.

Specification of Letters Patent. Patented Nov. 16, 1915.

Application filed April 15, 1913. Serial No. 761,166.

To all whom it may concern:

Be it known that I, WILLIS S. FARNSWORTH, a citizen of the United States, residing in the city and county of San Francisco and State of California, have invented new and useful Improvements in Lock-Guards, of which the following is a specification.

This invention relates to a lock guard and particularly pertains to an attachment for locks of the cylinder type for preventing backward turning of the cylinder after the lock has been operated.

It is the object of this invention to provide an attachment for cylinder or tumbler locks of the Yale type, by means of which turning of the lock cylinder after the lock has been operated will be prevented before the withdrawal of the key, and which attachment is especially designed for use in connection with coin-controlled locks for the purpose of preventing the accidental retraction of the bolt.

In the form of coin-controlled locks set forth in my co-pending application, filed June 20, 1912, Serial No. 704,745, the cylinder of a lock is turnable to throw the lock bolt only on the depositing of a certain coin: the key of the lock being removable therefrom after the coin has been deposited and the bolt thrown, the coin being retained on a temporary support during the time the lock is in its locked position and is released from its support on the reverse movement of the lock cylinder in retracting the lock bolt. It has been found by experience that persons unaccustomed to operating coin-controlled locks of the above character inadvertently turn the lock cylinder backward immediately after having deposited the coin and throwing the lock bolt; this inadvertent backward turning of the lock cylinder resulting in the unlocking of the lock and the release of the coin, thus restoring the lock to its normal inoperative position and preventing its use only on the deposit of another coin.

It is the purpose of this invention to prevent this accidental operation of the lock, and to provide a device which may be readily attached to the lock without necessitating any alteration of the lock structure, and which will not interfere with the operation of the lock only during such time as the key remains in the lock after the latter has been operated to throw the bolt.

The invention primarily resides in an attachment to the face of the lock incorporating a mechanism normally engageable with the lock cylinder to prevent its turning and adapted to be released from the lock cylinder by the insertion of a key, and so constructed as to permit of the lock being unlocked and locked after the key has been inserted therein; but which will prevent the lock being again unlocked until after the key has been withdrawn from the keyhole and re-inserted therein.

The invention further consists of the parts and the construction and combination of parts as hereinafter more fully described and claimed, having reference to the accompanying drawings, in which—

Figure 1 is a view in vertical section and elevation of the invention taken on the line *a—a* of Fig. 2, showing the attachment in its locking position. Fig. 2 is a vertical section and elevation on the line *b—b* of Fig. 1. Fig. 3 is a detail in elevation with parts removed, showing the device in the position assumed prior to the insertion of the key in the lock. Fig. 4 is a similar view, showing the parts as positioned on the initial insertion of the key in the lock. Fig. 5 is a modified form of the invention with parts broken away, showing it as positioned prior to the insertion of the key in the lock. Fig. 6 is a similar view, showing the parts as positioned on the insertion of the key in the lock. Fig. 7 is a view showing the parts in the position assumed when the key is turned in the lock to retract the bolt. Fig. 8 is a similar view, showing the parts in the locking position when the key is turned to lock the lock and prior to its removal. Fig. 9 is a front view of a coin-controlled lock with the invention applied. Fig. 10 is a side view of same. Fig. 11 is a rear view with the lock bolt retracted. Fig. 12 is a rear view with the lock bolt advanced.

In the drawings A represents the cylinder of an ordinary tumbler lock; the internal lock construction not being shown, as the operation of the invention is not dependent upon any portion of the lock structure other than the cylinder A. The escutcheon plate on the face of the lock is indicated at B, and the key for operating the lock is represented at C. The cylinder A is formed with the usual keyhole 2 for the reception of the shank of the key C, which key is adapted to

operate a series of tumblers in the cylinder A, not shown, in the usual manner to permit the turning of the cylinder A in the lock casing and the operation of the lock 5 bolt consequent thereto, as is well known.

In the form of the invention shown in Figs. 1 to 4, inclusive, a vertically reciprocal locking plate 3 is mounted on the outer face of the escutcheon plate B and is formed 10 with a central opening 4 through which the outer end of the cylinder A extends; the plate 3 being guided in its reciprocal movement by means of the sides of the opening 4 slidably contacting the sides of the cylinder 15 A, operating in conjunction with a pin 5 on the upper end of the plate 3, extending into a vertical slot or channel 6 formed on the escutcheon plate B. The plate 3 is designed to be normally retained in its uppermost position, for which purpose a spring 7 is provided. The spring 7 is here shown as consisting of a plate spring having its ends slidably secured to the plate 3, and its central portion bearing against the top of the 20 cylinder A under tension, in such manner as to normally retain the plate 3 in its uppermost position. The lower end of the opening 4 is arched and is adapted to extend into a groove or channel 8, formed on the underside of the cylinder A; the groove or channel 8 communicating with the keyhole 2. Formed in the arched portion of the plate 3 is a notch 9, which is disposed to register with the open underside of the keyhole 2 in 25 the channel 8; the vertical walls of the notch 9 being adapted to engage the sides of the shank of the key C when the latter is inserted in the lock, as particularly shown in Fig. 4. Slidably mounted in the lower end 30 of the cylinder A is a block 10, here shown as supported on a pin 11, carried on downwardly projecting portions 3' and 3^a on the plate 3. A helical spring 12, wound on the pin 11, bears between the projection 3' and 35 the end of the block 10 in such manner as to normally retain the block 10 with its outer end abutting against the projection 3^a, as shown in Fig. 3. Formed on the block 10 is an outwardly projecting lug 13, formed 40 with an inclined outer end; the lug 13 being so positioned on the block 10 as to be disposed immediately below the keyhole 2 when the block 10 is in its normal position, as shown in Fig. 3, and with the inclined end 45 of the lug 13 disposed in the path of a downwardly projecting shoulder 14, formed on the shank of the key C.

In the operation of this form of the invention let it be assumed that the parts are 50 in the position shown in Fig. 3; the plate 3 being in its uppermost position and the block 10 in its advanced position, and the key C removed from the keyhole 2. The parts being in this position, the key C on 55 being inserted into the keyhole 2 the shoul-

der 14 thereon is caused to engage the beveled outer end of the projection 13 on the plate 3 immediately before the key C reaches its innermost position in the lock; the key in moving to its innermost position in the 60 lock acting to move the plate 3 downward by reason of the shoulder 14 riding over the inclined outer end of the lug 13 into the position shown in Fig. 4. In this position the notch 9 on the plate 3 is moved out of the channel 8 on the cylinder A, and out of 65 engagement with the underside of the shank of the key C, so that the latter may be freely turned in the direction of the arrow in Fig. 4, to operate the lock. The key C on being 70 turned into the position indicated in dotted lines in Fig. 4, is moved from above the lug 13, thereby allowing the plate 3 to be restored to its normal uppermost position by the action of the spring 7. On turning 75 the key C in the reversed direction to operate the lock, the shoulder 14 engages the side of the lug 13 and moves the block 10 in opposition to the spring 12 into the position shown in Figs. 1 and 2. The key in 80 moving to its vertical position engages the arched portion of the plate 3 and moves the latter downwardly a short distance until the key comes in alignment with the notch 9, whereupon the spring 7 will operate to move 85 the plate 3 upwardly, so that the sides of the notch 9 will extend on each side of the shank of the key C, as shown in Fig. 1. When the parts are in this position, the key 90 C is locked against rotation in either direction, thus preventing the operation of the lock at this time. The key C, however, is now free to be withdrawn from the keyhole, 95 whereupon the block 10 will be returned to its normal position, as shown in Fig. 3, by 100 means of the spring 12, so that on the reinsertion of the key C the plate 3 will be moved to its lowermost position and permit the re-operation of the lock, as before described.

In the form of the invention shown in Figs. 5—6—7 and 8 the locking plate is 105 shown as pivotally mounted at 5', to have an oscillating movement in relation to the lock cylinder A. The block 10 in this instance is in the form of a piston and is supported in a cylinder 11' in which the spring 12 is mounted; the spring 12 bearing against the block 10 to retain the latter in its outermost position against a stop pin 3^b on the 110 plate 3. The operation of this form of the invention is substantially the same as described in reference to Figs. 1 to 4, inclusive; the projection 14 on the key C operating on the lug 13, carried by the block 10, to rock 115 the plate 3 on its pivot 5' when the key C is first inserted in the lock, as shown in Fig. 6, to move the notch 9 out of engagement with the shank of the key C. The key C is then free to turn in the direction of the ar- 120

row in Fig. 6, into the position shown in Fig. 7; the spring 7 acting to move the plate 3 to its normal position when the key C has been turned into the position shown in Fig. 7. 5 The lug 13 will then be positioned in the path of travel of the projection 14 on the key when the latter is turned in the direction of the arrow in Fig. 7, so as to be engaged by the latter and moved in opposition to the spring 12 into position shown in Fig. 8; the key C in moving from the position shown in Fig. 7 into the position shown in Fig. 8, oscillating the plate 3 a short distance in opposition to the spring 7, to allow 10 the shank of the key C to move into alignment with the notch 9; whereupon the latter will engage the shank of the key, as shown in Fig. 5, and prevent its being turned in either direction. 15 From the foregoing it will be seen that when the key C is engaged by the notch 9 on the plate 3, the cylinder A can not be rotated to operate the lock, thus preventing the actuating of any mechanism which depends 20 for its operation upon the rotation of the lock cylinder A.

The plate 3 and its connected parts are incased in the face of the escutcheon plate A in any suitable manner; a face plate 15 attached to the escutcheon plate B being here 25 shown as provided for that purpose.

As before stated, this invention is particularly applicable for use in combination with a coin-controlled lock. Such a lock is illustrated in Figs. 9—10—11 and 12. This lock consists of a bolt D, adapted to be operated by a bit E on the lock cylinder A; the bolt D being reciprocated by the rotation of the cylinder A by the key C in the usual well-known manner. The one essential feature in a coin-controlled lock of this character is that the key is unremovable from the lock when positioned at an angle in relation to the keyhole; the coin-controlled mechanism 35 consisting of a means for normally retaining the key in its angular position in the lock when the bolt is in its retracted position, which means can be released to permit the operation of the lock only on the depositing of a certain coin. This mechanism is constructed as follows: Mounted on the back of the escutcheon plate B, on opposite sides of the cylinder A, are downwardly depending arms 16 and 17, the upper ends of which 40 are pivotally connected to the face plate 15 by means of screws 18 which pass through curved slots 19 in the plate B. The slots 19 act in conjunction with the screws 18 to limit the rocking movement of the face plate 15 and the lock cylinder A in either direction. 45 The arms 16 and 17 extend downwardly adjacent to the rear side of the escutcheon plate B; the arm 17 being guided at its lower end between outwardly extending pins 20 and 20'. Formed on the lower end of the

arm 17 is a plate 21, the vertical edges of which are in slidable contact with the pins 20 and 20', which thus securely hold the lower end of the arm 17 against sidewise movement, but permit of its being oscillated by the rotation of the plate 15. The inner edge of the lower end of the arm 16 contacts the pin 20 and is held thereagainst by means of a plate spring 22, mounted on a bracket 23, carried by the escutcheon plate B, which spring bears against a pin 24 mounted on the arm 16. The pin 20 thus serves to limit the inward movement of the arm 16 and also limits its downward movement when actuated by the plate 15, by reason of its engagement with a shoulder 25 formed on the arm 16. It will be observed that the arm 16 may be rocked outwardly away from the pin 20, in opposition to the plate spring 22. Carried on the lower end of the arm 16 is an 50 inwardly extending plate 26, which projects over the lower end of the arm 17 and forms a coin-slot between the lower ends of the arms 16 and 17 in which a coin may be inserted through a slot 27 formed in the escutcheon plate B. A coin deposited in the slot 27 is designed to come to rest on a shoulder or abutment 28 formed on the inner edge of the arm 17, where it is supported by reason of its opposite edge bearing against the inner edge of the arm 16; the coin indicated at F resting on the shoulder 28 below an inwardly extending coin-pusher 29 carried by the arm 16.

When the key C is in the lock and the bolt 55 D is in its retracted position, the lower ends of the arms 16 and 17 will be positioned as shown in Fig. 11; in which position the downward movement of the arm 16 is prevented by means of the pin 20 and shoulder 25, so as to prevent the plate 15 and the lock cylinder A being rocked by the key C sufficiently far to allow the latter to be disposed in its vertical position in relation to the keyhole 2. By this construction the 60 key is prevented from being withdrawn from the lock and also locked against movement, thereby preventing the operation of the bolt D.

When it is desired to throw the bolt D 65 and withdraw the key C, a coin of a certain diameter or denomination is deposited in the slot 27 where it comes to rest upon the abutment 28 between the lower ends of the arms 16 and 17, as before described and as 70 shown in Fig. 11; the shoulder 25 being positioned a short distance above the pin 20 to permit of a limited downward movement of the arm 16 and consequent slight rotation of the plate 15. This movement of the plate 75 15 is effected by turning the key C after the coin F is deposited in such manner as to move the arm 16 in a downward direction and the arm 17 in an upward direction. The upward movement of the arm 17 car- 80

ries the coin F therewith so as to bring its upper edge into contact with the lower edge of the coin-pusher 29 on the arm 16. The downward movement of the arm 16 causes the member 29 to engage the coin F and move it downwardly in opposition to the arm 17, causing it to press against the shoulder 28 and force the arm 16 away from the arm 17, so as to cause the shoulder 25 to clear the pin 20. This will permit of a continued rotary movement of the key C and the plate 15, so as to throw the bolt D into the locked position and dispose the key C in the vertical position, which will allow of its being withdrawn from the lock. In thus advancing the bolt D, the arm 17 moves up and the arm 16 down. The coin on passing over the abutment 28 falls upon a stop-shoulder 30 on the inner edge of the lower end of the arm 17, where it comes to rest with its opposite edge against the inner edge of the arm 16, as shown in Fig. 12. The coin F in passing over the abutment 28 releases the lower end of the arm 16 so that it moves inwardly by the action of the spring 22, to throw the pin 20 into engagement with a V-shaped notch 31, formed on the inner edge of the arm 4. The coin F in moving downward passes below the pin 20. When the bolt D is in the advanced position, as shown in Fig. 12, the coin F will be supported on the stop-shoulder 30 and against the inner edge of the arm 16. The key will be prevented from being turned backward and consequently retracting the bolt D by reason of the engagement of the shank of the key with the notch 8 on the locking-plate 9, as before described. This is necessary in order to prevent the accidental retraction of the bolt D and necessitating the removal of the key from the lock and its re-insertion therein in order to retract the bolt. On the re-insertion of the key in the lock and turning of the lock cylinder A to retract the bolt D, the arm 17 will be moved in a downward direction and the arm 16 in an upward direction, the projection 28 on the arm 17 forcing the coin F downward below the pin 20, whereupon it becomes released and is deposited in any suitable receptacle. The arm 16 in moving upward is moved outward by reason of the inclined face of the notch 31 riding over the pin 20 so as to permit the coin F passing between the lower end of the arm 16 and the shoulder 30 on the arm 17. The moment the coin F is released from between the shoulder 30 and the arm 16, the latter is moved back to its normal position by means of the plate spring 22, thereby repositioning the pin 20 below the shoulder 25 on the arm 16 in such position as to prevent the operation of the lock until another coin has been deposited.

Having thus described my invention, what

I claim and desire to secure by Letters Patent is:

1. The combination with the cylinder of a lock and a key therefor, of a plate formed with a notch adapted to engage the shank 70 of the key to prevent its rotation when the latter is inserted in the cylinder, means on the plate operable by the key to disengage the plate from the key to permit the operation of the key in the cylinder, and means 75 by which the key will be engaged by the notch when positioned for withdrawal from the lock to prevent the cylinder and key being rotated in either direction.

2. The combination with a revoluble lock 80 cylinder adapted to receive a key and the key therefor, of means for engaging the key to prevent its rotation on its insertion in the cylinder, means for disconnecting the key from the engaging means operable by the 85 key to permit the cylinder and key being rotated, and means by which the key will be re-engaged when the cylinder and key are restored to their normal position to prevent turning of the key and cylinder. 90

3. The combination with a key and revoluble lock cylinder operable thereby, of means independent of the cylinder for engaging the shank of the key to prevent its rotation when the latter is inserted in the 95 cylinder, means actuated by the key for releasing the key and cylinder from the engaging means to permit the key and cylinder being turned, and means operated by the key for causing its reengagement on 100 turning the key and the cylinder to their normal position by which the key and cylinder will be locked against rotation. 105

4. The combination with a key and a lock element operable thereby, of a plate formed 110 with a notch adapted to engage the shank of a key to prevent its rotation when the latter is inserted in the keyhole, a spring for normally holding the plate in its engaging position, means on the plate operable 115 by the key on its insertion in the keyhole for moving the plate in opposition to the spring to release the key and permit its being turned to operate the lock, comprising a lug carried by the notched plate arranged 120 in alignment with the keyhole and in the path of travel of a projection on the key when the latter is being inserted in the lock, and means by which the lug may be moved out of alignment with the keyhole operated 125 by the key when the latter is restored to its removable position after operating the lock, to allow the notched plate to reengage the key and prevent its turning.

5. The combination with a key and revoluble lock cylinder operable thereby, of means independent of the cylinder for engaging the shank of the key to prevent its rotation when the latter is inserted in the 130 cylinder, means actuated by a projection on

the handle of the key for releasing the key and cylinder from the engaging means to permit the key and cylinder being turned, and means operated by the key for causing 5 its reengagement on turning the key and the cylinder to their normal position by which the key and cylinder will be locked against rotation.

In testimony whereof I have hereunto set my hand in the presence of two subscribing 10 witnesses.

WILLIS SMITH FARNSWORTH.
